ROBERTO T. E. OKRASSA, OF ANTIGUA, GUATEMALA.

SUGAR MILL OR CANE CRUSHER.

Application filed May 3, 1923. Serial No. 638,486.

To all whom it may concern:

Be it known that I, ROBERTO T. E. OKRASSA, a citizen of Germany, and a resident of the city of Antigua, Guatemala, Central America, have invented a new and Improved Sugar Mill or Cane Crusher, of which the following is a full, clear, and exact description.

This invention relates to sugar mill machinery and particularly to an improved cane crushing structure and has for an object to provide an improved construction wherein the pressure on the crushing rolls is automatically maintained at a given tension regardless of the quantity of material passing therethrough.

Another object of the invention is to provide an improved cane crushing construction wherein a conveyer or guide is provided for directing the crushed cane from one set of rollers to another set.

A still further object of the invention is to provide in a cane crushing apparatus a combined guide for guiding cane from one set of rollers to another and a scraper for one of the rollers.

In the accompanying drawings—

Figure 1 is a side view with certain parts broken away disclosing a cane crushing mechanism embodying the invention.

Figure 2 is a front view of the structure shown in Figure 1 with the cane chute and certain other parts removed, the parts being shown on a reduced scale.

Figure 3 is a front view of the cane conveyer or guide embodying certain features of the invention.

Figure 4 is a sectional view through Figure 3 approximately on line 4—4.

Figure 5 is a top plan view of the guide shown in Figure 4.

Figure 6 is a fragmentary sectional view through Figure 1 approximately on line 6—6.

Figure 7 is a view somewhat similar to Figure 4 but disclosing a modified construction, the section, however, being taken on line 7—7 of Figure 8.

Figure 8 is a front view of the structure shown in Figure 7, the same illustrating a modified structure to that illustrated in Figure 3.

Referring to the accompanying drawings by numeral, 1 indicates a base of any desired kind, as for instance, a casting which is provided with a drain pan 2 for receiving

the juices of the cane and directing the same to a suitable discharge point. On the base 1 is arranged suitable journal boxes 3 and 4 held in place in any suitable manner, as for instance, by the anchor bolts 5. The construction just described is old and well known and, therefore, forms no part of the present invention except in combination with certain other parts hereinafter fully described.

The journal boxes 3 and 4, however, are made slightly different from those heretofore used in that they are left open at the top and incline somewhat towards each other for receiving the respective eccentrics 6 which eccentrics are formed integral with or rigidly secured to the respective levers 7. It will be noted that there are four levers 7 and each lever is provided with an eccentric 6 and rotatably mounted in the respective journal boxes 3 and 4. These journal boxes are open as just described so that these eccentrics may be dropped therein and then function in the proper manner. The levers 7 are arranged in pairs and the respective pairs are provided with pins 8 and 9 respectively, the pin 9 also accommodating the yoke 10 to which the end of a chain 11 is secured. The respective pins are provided with any desired number of pulleys 12 and which, with the chain 10 is weaved thereover and then passed over a pulley 13 arranged at a distant point so that the weight 14 secured to the end of the chain may pull substantially in a horizontal direction on the chain as it leaves the pulleys 12. The weight 14 will give a continuous tendency to the levers 7 to move towards each other and, consequently, to always provide the same pressure against the cane whether there is a large load or a small load.

In order to prevent the rollers 15, 16 and 17 from grinding together, suitable adjustable stops 18 and 19 are provided for limiting the inward swinging movement of the levers 7. An eccentrically positioned aperture is arranged in each of the eccentrics 6 for accommodating the respective shafts 20 of the respective rollers 15 and 17 whereby as the levers 7 rock back and forth and the eccentrics 6 function, the rollers 15 and 17 will move toward and from each other and also toward and from the roller 16 which is mounted in any desired form of journal box and is held in a fixed position. It will be noted from Figure 1 that the rollers are

arranged in a triangle and that the cane is fed in through the chute 21 so that it may pass between the rollers 15 and 16. From these rollers the cane passes through the 5 rollers 16 and 17 and finally out through the discharge chute 22.

In order that the crushed or partially crushed cane may freely pass the rollers 15 and 17, a guide or conveying block 23 is 10 provided which may be a casting and which is provided with upstanding guiding flanges 24 and 25 adapted to straddle the roller 16. A plurality of notches 26 are arranged in 15 one edge whereby a toothed structure is presented, said notches being provided so that the cane may be properly guided to the roller 17 while the juice may drop down into the pan 2.

From Figures 3 and 4, it will be noted 20 that the block 23 is provided with a pair of depending bearing lugs 27 for receiving the respective supporting bars 28 and 29, each of which has an adjustable bearing pin 30 at the bottom resting on the respective 25 bearing blocks 31. The block 23 also is provided with a pair of depending arc-shaped arms 32, the lower ends of which accommodate a friction plate 33 adapted to bear 30 against the roller 15 while the block 23 has an upper bearing plate 34 also designed to bear more or less tightly against the roller 15 for causing the cane to leave the roller and pass over the block 23. It will be noted 35 that the weight of the block 23 and associated parts bearing against the supporting bars 28 and 29 will cause the parts to press more or less firmly against the roller 15, which pressure is augmented somewhat by the downward pressure of the cane 40 as it passes over the guiding block 23. Also, means have been provided for holding the block 23 in place and the friction plate 34 properly pressing against the roller. This means consists of a pair of links 35, 45 there being one link arranged at each end of the block 23. Each of these links is provided with an elongated opening 36 accommodating the respective journal pins 37 extending from the ends of the block 23. The 50 end of the link opposite that carrying the slot 36 is provided with a comparatively large aperture designed to accommodate the disk 38 which is provided with an eccentrically positioned aperture through which the shaft 20 extends. A pair of small guiding plates 39 is rigidly secured to the disk 38 and arranged to straddle part of the links 35 while substantially on the diametrically opposite side is arranged a U-shaped member 40 having the legs riveted or otherwise secured to the disk 38. The U-shaped member 40 carries a set screw 41 which is adapted to be screwed down and pinch the links 35 so as to lock the disk 38 and the links 60 65 35 together. In case of wearing of the roll-

er 15 or of the plates 33 and 34, screw 41 may be loosened and the eccentrically mounted disk 38 rotated somewhat until the parts are tight and then the set screw 41 tightened. In this way, the position of the block 23 and associated parts may be readily adjusted to take care of wear or to provide any desired tightness or looseness of connection. 70

When the crusher is in use, cane is fed 75 into the chute 21 and as it moves between the rollers 15 and 16, these rollers may separate somewhat if the supply is great, said separation causing the levers 7 to swing but by reason of the arrangement of the 80 weight 14 and associated parts, a continued even pressure will be supplied. As the crushed or partially crushed cane passes the rollers 15 and 16, it will engage the block 23 and be guided thereby to the rollers 16 and 17 or a second crushing operation is provided so that substantially all of the juice will be squeezed from the cane. If desired, the roller 15 may be set to be constantly further from the roller 16 than the 85 roller 17 is from the roller 16. This will cause a preliminary crushing and then a 90 final crushing.

In order to adjust the rollers in respect 95 to the levers 7, any desired number of bolts 42 extend through suitable apertures in the eccentrics 6 and through the respective levers 7. By removing these bolts and shifting the eccentrics 6 and then re-applying the bolts, different adjustments may be secured. Heretofore it has been difficult to 100 properly guide the cane from the roller 15 to the roller 17 and quite often the mass of crushed or partially crushed cane would accumulate between these two rollers and prevent a proper functioning of the apparatus. By providing the contact plate 34, a substantial shaving action of roller 15 will 105 be provided and the matter thus shaved from the roller 15 will freely pass over the block 23 to the roller 17 without clogging any part of the mechanism and the finally 110 crushed cane or pulp will be discharged out the chute 22.

In Figures 7 and 8 a slightly modified 115 construction is shown in respect to the guiding block 23. In this form of the invention it will be observed that the block 23' is provided merely with a shaving or wearing plate 34' and the plate 33 is eliminated. It will also be noted that in this form of the 120 invention a single integral lug 43 extends from the lower part of the block 23' and projects through a bracing bar 44, which bar is connected in any desired manner with the supporting bars 28' and 29'. A nut 45 is screwed onto the lug 43 so as to clamp the parts firmly together while allowing the bars 28' and 29' to rock freely in the 125 respective supports 31'. 130

What I claim is:—

1. A crusher for cane mills, comprising three crushing rollers arranged in a triangle, a pair of levers connected with each 5 of the two lower rollers, means including a flexible member and weight acting thereon co-acting with said levers and rollers for automatically causing the levers to swing the lower rollers toward and from each 10 other, and means for guiding cane to said rollers.

2. In a cane crushing apparatus, a plurality of crushing rollers and guiding means for guiding cane from one roller to the 15 other, said guiding means including a guiding block having a plurality of notches, and a pair of depending arms, a pair of roller engaging plates connected to said block and to the arms thereof, means for holding said 20 plates in frictional engagement with one of said rollers, and means for supporting said block while allowing a limited swinging movement thereof.

3. In a cane crushing apparatus, a plurality of crushing rollers and guiding means for guiding the cane from one roller to the other, said guiding means including a guiding block frictionally engaging one 25 of the rollers, means for supporting the block, and means for holding the block

against one of the rollers, said last mentioned means including a pair of links pivotally connected with the block, an eccentrically mounted disk rotatably mounted in each of said links, and means for locking the 35 disks in different positions in respect to the links.

4. A cane crushing apparatus of the character described, comprising a fixed crushing roller, a pair of movable crushing rollers co-acting with the fixed crushing 40 roller, each of the movable crushing rollers having a shaft extending therefrom, eccentric members mounted on said shafts, a bearing block for each of said eccentric members, a pair of levers for each of said movable rollers, means for clamping the eccentrics to the respective levers so that when the levers are swung back and forth the eccentrics will be rotated and the movable 45 rollers will be moved substantially toward and from each other, a pulley carried by each of said levers near the upper end, a chain secured to one of the levers and reeve over said pulleys, and a weight acting on said chain for pulling the same so as to give the levers a tendency to move towards each other and consequently swing said movable rollers toward each other. 50
